UNITED STATES PATENT OFFICE

96,520

DESIGN FOR A HAND BAG

Keriacos Thucaky, Haverhill, Mass.

Application June 1, 1935, Serial No. 57,102

Term of patent 3½ years

To all whom it may concern:

Be it known that I, Keriacos Thucaky, a citizen of the United States residing at Haverhill, in the county of Essex and State of Massachusetts, have invented a new, original, and ornamental Design for Hand Bag, of which the following is a specification, reference being had to the accompanying drawing, forming part thereof.

Figures 1 and 2 are side and edge elevational views respectively of a hand bag showing my new design.

I claim:

The ornamental design for a hand bag, as shown.

KERIACOS THUCAKY.
